UNITED STATES PATENT OFFICE.

ROBERT S. WIESENFELD, OF BALTIMORE, MARYLAND, ASSIGNOR OF ONE-HALF TO JOSEPH CASTELBERG, OF BALTIMORE, MARYLAND.

AUTOMATIC CLOCK.

SPECIFICATION forming part of Letters Patent No. 715,226, dated December 2, 1902.

Application filed July 23, 1902. Serial No. 116,659. (No model.)

To all whom it may concern:

Be it known that I, ROBERT S. WIESENFELD, a citizen of the United States, residing at Baltimore, in the State of Maryland, have invented 5 certain new and useful Improvements in Automatic Clocks; and I do declare the following to be a full, clear, and exact description of the invention, such as will enable others skilled in the art to which it appertains 10 to make and use the same, reference being had to the accompanying drawings, and to the figures of reference marked thereon, which form a part of this specification.

My invention relates to advertising-clocks; 15 and the objects of the same are to provide means for attaching a series of advertisements to the pedestal of a clock in such a manner that the advertisements may be revolved at intervals to give to each advertiser an equal 20 display at the front or face side of the clock.

Another object is to provide means for attaching a thermometer at the top of the clock and to provide suitable openings in the clock-frame for the insertion of weather reports 25 or other desirable information. An opening at the side of the clock-frame is provided, through which a rotary calendar may be readily seen to give the day of the month and week.

30 The objects referred to are attained by means of the construction illustrated in the accompanying drawings, in which—

Figure 1 is a front elevation of a clock made in accordance with my invention. Fig. 2 is 35 a side elevation and partial section of the same. Fig. 3 is a transverse section on the line *x x*.

The clock 1 is of any suitable style and may be either an electric or a spring motor 40 clock. The clock-frame is provided with an opening 2 for displaying a weather report, and at the side of the frame a similar opening 3 is provided for a rotary calendar. A thermometer 4 is attached to a sign or advertise- 45 ment 5 at the top of the clock, and a series of electric-light bulbs 6 are arranged in a circle around the face of the clock to illuminate the

clock at night. The clock-head is supported upon a rod or spindle 7, and the lower end of the spindle is rigidly secured to a base 8. 50 Mounted upon the spindle or rod 7 is a rotatable frame 9, which consists of a tube 10, having square heads 11 12. At the corners of the heads strips or corner-posts 13 extend from one head to the other and are properly secured 55 to form a light strong frame to support a series of advertisements or signs 14. These signs are connected together by hooks 15 and may be transparent or opaque. If transparent signs are to be used, electric or other lights 60 may be arranged within the frame back of the signs to illuminate them. The frame 9 may be rotated from time to time either by hand or by means of a spring or electric motor in order that each advertiser may have 65 the benefit of equal display at the front of the clock. By means of the hooks 15 the signs may be detachably connected together, and new signs may be readily attached when desired. 70

A clock made in accordance with my invention may be rendered very attractive and useful and at the same time be of considerable value to advertisers.

What I desire to secure by Letters Patent 75 and claim is—

The herein-described advertising-clock, consisting of a base, a rod secured centrally to the base and having a clock rigidly secured to its upper end, a rectangular skeleton frame 80 consisting of corner-strips, top and bottom pieces, and a tube extending centrally from the top piece to the bottom piece, the central rod passing through the tube to permit the frame to revolve on the rod between the base 85 and clock, and a series of placards removably suspended from the frame by hooks, substantially as described.

In testimony whereof I affix my signature in presence of two witnesses.

ROBERT S. WIESENFELD.
